UNITED STATES PATENT OFFICE.

HARRY C. SINCLAIR, OF ST. MICHAELS, MARYLAND, ASSIGNOR TO
ROBERT A. BONNER, OF BALTIMORE, MARYLAND.

CIRCULAR-LETTER-PRINTING MACHINE.

No. 829,440.

Specification of Letters Patent.

Patented Aug. 28, 1906.

Application filed November 21, 1905. Serial No. 288,949.

To all whom it may concern:

Be it known that I, HARRY C. SINCLAIR, a citizen of the United States, residing at St. Michaels, in the county of Talbot and State of Maryland, have invented certain new and useful Improvements in Circular - Letter-Printing Machines; and I do hereby declare the following to be a full, clear, and exact description of the same, reference being had, to the accompanying drawings, forming a part of this specification, and to the letters of reference marked thereon.

This invention relates to improvements in mechanism for printing circular-letters. Circular-letters in order to receive proper attention and consideration must simulate ordinary personal communications to such an extent as to be practically indistinguishable therefrom, and hence such letters must, like ordinary personal communications, each embody the name, address, and salutation appropriate for the person to whom the letter is sent. This requirement necessitates the printing on the letters of matter differing from each and all of the other letters of the same class—that is to say, while the body of all of the letters, including the emphasized matter and signature, may be duplicates, the name, address, and salutation must be made appropriate for each individual letter.

It is the object of the present invention to provide a machine which will print letters of the desired character both with respect to the letter-head, the body of the letter, the emphasized matter, the signature, the name, the address, and the salutation of the addressee, which machine shall be automatic in its action and the mechanisms for performing the several steps to be hereinafter described so correlated through their driving and controlling parts that the personal attendance and attention is practically limited to the supplying of material, paper, envelops, &c., in bulk and to the removal of the printed letters and envelops ready for folding and mailing.

Another important object of the invention is to provide a machine having a very large capacity and at the same time so constructed as to impress upon each letter the characteristics of a personal communication, such as can ordinarily be obtained only by preparing the letters individually on an ordinary type-writing machine.

A further object of the invention is to provide a machine which will print a succession of letters such as hereinbefore referred to and which will print in connection therewith a succession of envelops corresponding to the letters and each envelop bearing a name and address similar to the name and address on one of the letters.

A further object of the invention is to provide a machine for printing circular letters or envelops, or both, in which the characters constituting the name, address, and salutation may be impressed individually and simultaneously in different lines, whereby the whole matter may be impressed during a single passage of the paper through the machine.

A further object of the invention is to provide a machine for printing the name, address, and salutation by individual character impressions effected simultaneously in different lines and controlled by a single punched card or controller, one for each person to whom a letter is to be sent.

The invention will be best understood by first describing the assemblage and general characteristics of the several component parts, followed by a detailed description of each of the parts.

Referring to the accompanying drawings, Figure 1 is a superficial side elevation of a machine embodying the present improvements, portions of the frame and mechanism being broken away and underlying parts omitted for the sake of perspicuity. Fig. 2 is a superficial top plan view of the machine, showing the general location and arrangement of the parts, underlying parts being omitted, as in Fig. 1. Fig. 3 is an end elevation corresponding to Figs. 1 and 2 in that underlying parts are omitted. Fig. 4 is a plan view showing the driving-gear for the three feed mechanisms—i. e., the paper-feed, the envelop-feed, and the card or controller feed. Fig. 5 is a side elevation of that portion of the mechanism shown at the right-hand end of Fig. 1 and adapted to draw a strip of paper past the printing mechanism with a motion which may be described as a long feed or jump and a succession of intermittent short feeds or jumps, as will be hereinafter more fully explained. Fig. 6 is a plan view of the paper-feeding mechanism shown in Fig. 5. Fig. 7 is an elevation looking at the mechanism from the right-hand side of Fig.

5. Fig. 8 is a perspective view of the gearing for effecting the intermittent movements. Fig. 9 is a perspective view of the severing-knife with its operating mechanism, and Fig. 10 is a detail of the knife-operating mechanism. Fig. 11 is a vertical section, partially in elevation, of the mechanism at the left-hand end of Fig. 1, showing the details of construction of the inking mechanism for the letter-head-printing portion of the machine and also the platen and chase for that portion of the machine for printing the body of the letter. Figs. 12, 13, and 14 are detail diagrammatic views illustrating the movement of the letter-head-printing chase and inking-rollers therefor. Fig. 15 is a transverse section through the chase and platen for printing the body of the letter and showing in elevation the operating mechanism, together with the ink-ribbon-feeding devices. Fig. 16 is a detail plan view of the ink-ribbon-feeding devices for the mechanism for printing the body of the letter and emphasized portions of the body of the letter. Fig. 17 is a detail perspective view illustrating the ink-ribbon-feeding and ribbon-feed-reversing mechanism. Figs. 18 and 19 are detail views showing the paper and its guiding and supporting clips. Fig. 20 is a longitudinal section elevation of the signature-printing mechanism. Fig. 21 is a similar view, but taken in a vertical plane at right angles to Fig. 20. Figs. 22 and 23 are detail perspective views of portions of the adjusting, guiding, and controlling parts of the signature-printing mechanism. Fig. 24 is an elevation, partly in section and partly broken away, of the name, address, and salutation printing mechanism. Fig. 25 is a similar view looking from a point at right angles to Fig. 24 and showing the operating mechanism for the type-bars. Fig. 26 is a diagrammatic elevation showing the means for controlling and operating the type-bars from a perforated card. Fig. 27 is a top plan view of the mechanism shown in Figs. 24 and 25, a few only of the duplicate parts being shown in position in order to avoid confusion of lines in the illustration. Fig. 28 is a sectional elevation looking at the mechanism shown in the upper portion of Fig. 2 from the right-hand end and constituting the controller or card handling mechanism. Fig. 29 is a top plan view of the mechanism shown in Fig. 28, omitting the driving-gear. Fig. 30 is a section in a vertical plane through the card-handling portion of the mechanism with parts in elevation. Fig. 31 is a sectional perspective view showing the contacts in the circuits controlling the name, address, and salutation printing mechanism. Fig. 32 is a section at right angles to the plane of the section in Fig. 31. Fig. 33 is a detail perspective view of the reciprocatory feeder for the cards with parts separated from each other. Fig. 34 is a detail perspective view of the intermittent feed-controlling gearing of the card-feeding mechanism. Figs. 35 and 36 are detail sectional elevations of the reciprocatory card-feeding mechanism shown in different positions assumed by it during the card-feeding operation. Fig. 37 is a diagrammatic plan view of a card punched for controlling the printing of a name, address, and salutation. Fig. 38 is a top plan view of the envelop-feeding mechanism with portions broken away and the driving mechanism omitted. Fig. 39 is a sectional elevation taken transversely of the envelop-hopper. Fig. 40 is a similar view looking at the mechanism shown in Fig. 39 from the right-hand side. Fig. 41 is a perspective view showing the gearing for the envelop-feeding mechanism, together with a portion of said feeding mechanism itself. Figs. 42 and 43 are detail plan views of portions of the gearing omitted in Fig. 41. Figs. 44 and 45 are a plan and sectional elevation, respectively, of the reciprocatory envelop-feeding mechanism. Fig. 46 is a detail perspective view of a portion of the mechanism shown in Figs. 44 and 45. Fig. 47 is a plan view, partly broken away and partly in section, showing the mechanism for adjusting the envelop-feeding mechanism for the accommodation of envelopes of different sizes. Like letters of reference in the several figures indicate the same parts.

The machine of the present invention is designed for printing the letters on a web of paper fed to the machine or through the machine from a suitable roll located at one end thereof. During its transit through the machine impressions are applied to the web in proper position to constitute the letter-head, body of the letter, and data, including the name, address, &c., going to make up a complete letter of the character heretofore specified, and as a final step the web of paper is severed into separate sheets ready for folding and mailing. In connection with the printing mechanism for the letter a corresponding printing mechanism for the envelopes is provided, and the envelop-feed and letter-feed are arranged to advance the respective letters and envelopes in proper relation to each other, so that at a proper stage in the operation the name and address may be printed upon both the letter and the envelop simultaneously and under the control of the same controlling device.

Referring to Figs. 1 to 4 of the accompanying drawings, and particularly to Fig. 1, the paper-supply roll is shown at A with a tension-regulator or slack-take-up A', supported in a loop of the paper web. From the said take-up the web extends through suitable guides or clips and through the printing mechanism to the right-hand end of the machine, where it passes between feed-rollers.

B, geared together for simultaneous rotation and held toward each other by spring-pressure, as is usual in web-feeding mechanisms. The feed-rollers B are adapted to draw the paper with a straight direct pull through the printing mechanism and to project the same through between the jaws of a cutter C, which severs the web into appropriate letter-sheets. As the web enters the machine from the supply-roll A it passes first through a mechanism (designated generally by the letter D) for printing the letter-heads of the several letters, thence through a mechanism E for printing the body of the letter, thence through a mechanism F for printing the emphasized portion of the letter, thence through a mechanism G for printing the signatures, and thence through a mechanism H for printing the names, addresses, and salutations, all of said mechanisms being correlated so as to perform their operations in proper sequence and to print in proper relation to each other upon the sheets for producing a complete and perfect letter.

25 By referring to Figs. 2 and 3 it will be seen that the machine embodies, in addition to the paper handling and printing mechanism referred to, a mechanism for handling and printing envelopes, the latter being arranged parallel with the former, and, in general, the printing mechanism for printing the business-cards on the envelopes is designated by the letter K, while the mechanism for printing the names and addresses on the envelopes is indicated at L in proximity to the mechanism H for printing the names and addresses on the letters themselves.

The controller or perforated card-handling mechanism is designated generally by the letter M and is preferably, though not necessarily, located in proximity to the name and address printing portions of the machine and in any event is so located as to be conveniently controlled itself through the mechanism which controls the feed of the paper and envelopes in order that the proper relations may be maintained between the several parts of the machine.

The main shaft N of the machine is preferably a crank-shaft for reciprocating the beds of the parts D, E, F, G, and K, as will be presently explained, and its motion may be derived from any suitable prime mover through a shaft N', connected by gearing, such as bevel-gears n , as shown in Fig. 4. Connected with the main shaft N by gearing, including bevel-gears n' and vertical shaft n^2 , is a feed drive-shaft O, which latter through bevel-gears o drives a shaft O', leading to the envelop-feed, and through gears o' also drives a shaft O² for the perforated card or controller feed. While not essential, it is preferred that the shafts O, O', and O² should rotate at a uniform speed in order that the

feed mechanisms may more conveniently be 65 made to synchronize.

The feeding mechanisms are in many respects essentially similar—that is to say, they all are adapted to feed rapidly for a given distance and then to feed with a succession of short jumps, these movements in each being arranged to occur in sequence, so as to present the paper and envelopes first in position for receiving an impression or impressions which may extend for the full 75 width of a given letter-sheet and then present the paper to the mechanism for impressing individual characters in succession.

In order that the mechanism may be more clearly understood, that portion designed 80 for feeding the paper will first be described. This mechanism is best shown in Figs. 5 to 10, inclusive, and by reference to said figures it will be seen that the shaft O carries two gear-wheels O³ O⁴, the latter being a mutilated gear-wheel—i. e., having teeth throughout a portion of its periphery entirely omitted. Meshing with the gear-wheel O³ is a pinion O⁵, fast on a shaft O⁶, said shaft O⁶ also carrying fast thereon a gear-wheel O⁷, 90 adapted to mesh with a gear-wheel O⁸ on the end of the shaft of the lower feed-roll B. The gear O⁸ is a mutilated gear, whereby when the blank or space is in proximity to the gear-wheel O⁷ motion will not be transmitted to the feed-roll, but the latter will remain at rest or be advanced by other mechanism to be presently described. The feed-rolls B, it will be understood, are connected together by suitable gearing, as usual in paper-feeding machines, and the shaft of the lower roll, in addition to the mutilated gear-wheel O⁸, carries a worm-gear O⁹, which latter is also a mutilated gear, but at certain times meshes with a worm O¹⁰, the length 95 and inclination of the worm being such that less than a complete rotation will advance the feed-roll a distance of one tooth on the worm-gear. This advance corresponds to a step-by-step feed of the paper for properly 100 presenting it to the individual character-impression mechanism; but the length of said worm is less than a complete turn, whereby a dwell or pause in the feed is secured, and if the worm-shaft be arrested with the end of 105 the worm out of the path of the teeth in the worm-gear the latter will be left free to rotate. The worm-shaft is rotated through a bevel pinion and gear O¹¹, the latter being journaled on the shaft O⁶, but having keyed thereto a pinion O¹², with its teeth in position 110 to mesh with the teeth of the mutilated gear O⁴ on the feed drive-shaft O.

The relation of the gears and mutilated gear-wheels is such that as the feed-roller is 115 rotated by the train of gears O³, O⁵, O⁷, and O⁸ the teeth of the latter gear—namely, gear O⁸—will move out of mesh with the gear O⁷ at

such a time that the first tooth of the worm-gear O^9 will be in position to be engaged by the worm O^{10} during its first rotation, and the feed-rollers will come to rest with the parts 5 in such position. The blank space in the gear-wheel O^4 is so proportioned that at the proper instant, as will be hereinafter described, the teeth of said gear-wheel O^4 will mesh with the pinion O^{12} and through the 10 gear and pinion O^{11} rotate the worm O^{10} in a direction to advance the feed-rollers with a succession of short feed movements in extent corresponding to the feed movement necessary between the impression of each individual character in the name, address, and salutation of the letter. As the last tooth of the 15 worm-gear O^9 is advanced by the worm O^{10} the first tooth of the mutilated gear O^8 will again be brought into mesh with the gear O^7 , and the feed-rolls B will be again rotated rapidly and continuously for a distance corresponding to the necessary feed of the paper between the last character-space of the name, address, or salutation and the beginning of 20 the first character of the next name, address, or salutation of the next succeeding letter. The impressions of the letter-heads, bodies of the letter, emphasized portions, and signatures are made during the period of rest 25 immediately preceding the beginning of the step-by-step or succession of short feed movements, and this interval is in all instances made sufficiently long to permit of the impressions being made without danger of smearing the work and without danger of injuring the paper web by attempting to advance the same while held by the printing mechanism.

As before stated, the drive-gearing for the 30 feeding devices of the paper, envelopes, and cards or controllers in many respects each resembles the other, and in order that the analogy and relation between these several parts may be hereinafter more clearly comprehended a description of the other two is in order at this point.

By reference to Figs. 4, 28, and 34 it will be seen that the shaft O^2 carries two gear-wheels P^8 and P^4 , corresponding to the gear-wheels O^8 and O^4 on the shaft O . Meshing with the gear-wheels P^8 and P^4 are gears P^5 and P^{12} , the latter being fast on the hub of a gear-wheel P^{11} , meshing with a pinion P^{11} and adapted to rotate a worm P^{10} . The gear-wheel P^{11} is journaled and the gear-wheel P^5 is fast on a shaft P^5 , and a miter gear-wheel P^7 , corresponding to the gear-wheel O^7 of the paper-feed, is also fast on the shaft P^5 . The 55 vertical shaft P^{13} carries mutilated gear-wheels P^8 and P^9 , corresponding to the mutilated gear-wheels O^8 and O^9 in the paper-feed, save that the number of teeth in the wheel P^8 is less than the number of teeth in the wheel O^8 , inasmuch as it is necessary to 60 feed the cards or controllers but a relatively

short distance between the intermittent or step-by-step feeds.

The gearing for the feed mechanism of the envelop-feed is best shown in Figs. 39, 40, 41, 42, and 43. Thus, referring to said figures, it 70 will be seen that the shaft O' , Fig. 4, is provided with two gear-wheels Q^3 Q^4 , adapted to mesh with gear-wheels Q^5 Q^{12} , the former being fast on the shaft q^5 and the latter being fast on the hub of a gear Q^{11} , journaled on the 75 shaft q^5 . In addition the shaft q^5 carries a gear-wheel Q^7 , the latter adapted to mesh with a mutilated gear-wheel Q^8 on a vertical shaft Q^{13} . The vertical shaft Q^{13} also carries a mutilated gear Q^9 , the teeth of which are 80 adapted to mesh with a worm Q^{10} , driven by a pinion q^{11} , meshing with the gear-wheel Q^{11} . In the gearing for the feeding mechanism described it will be understood at once that the 85 number of teeth in the mutilated gear-wheels O^8 , P^8 , and Q^8 determines the length of the long feed of the paper, envelopes, and cards or controllers, respectively, and it is obvious that the length of this long feed should be in proportion to the distance to be moved between the intermittent or step-by-step feeds 90 imparted by the worms and worm-wheels. In correlated gearing of this character where the short intermittent or step-by-step feeds are to be effected simultaneously and in alternation with long feeds of different extent it is necessary that some means should be adopted whereby the short or step-by-step feeds will commence at exactly the same instant. This result in the present mechanism is accomplished by arranging the first 95 tooth of the mutilated gears O^4 , P^4 , and Q^4 so that they will all come into action simultaneously, and consequently will all inaugurate the step-by-step feeds at the same time. The 100 dwells or pauses in the step-by-step feeds is secured by making the worms O^{10} P^{10} Q^{10} discontinuous—that is to say, during a portion of the rotation of these worms the feed takes place and during the remainder of the rotation of these worms the feed is at rest, and it is during the latter periods that the impressions of the individual characters going to 105 make up the name, address, and salutation are impressed. Said worms come into action simultaneously, rotate in synchronism, and come to rest simultaneously. Likewise the long feeds come into action simultaneously, but are arrested at different times—that is to say, the feed of the cards or controllers being 110 the shortest the number of teeth in the mutilated gear P^8 is less than the number of teeth in the mutilated gears O^8 and Q^8 , and the number of teeth in the latter gears is proportioned to the width of the paper to constitute 115 the letter-sheets and the length of the envelopes.

Printing mechanism.—Referring to Figs. 1, 3, and 11 to 21, it will be seen that the mechanism for printing the letter-heads, body of 120

the letter, signatures, and business or return cards on the envelopes consists, essentially, of reciprocating beds adapted to coöperate with suitable platens. Thus in Fig. 11 the bed 5 which carries the chase or chases for printing the letter-heads, body of the letter, and accentuated matter is indicated by the letter D'. The respective impression-surfaces are indicated by the letters d' e' f, and the respective platens are indicated by the letters d', e', and f'.

While reciprocating beds for the several impression-surfaces d', e', and f' might be made separate from each other, yet for convenience in manufacture they are shown as connected in one structure D'; but in order that the pressure on the respective chases may be equalized the bed is provided with duplicate operating mechanisms, one in 15 juxtaposition to each chase. The operating mechanism shown consists of links E', extending upwardly and pivotally connected with levers E', pivoted at one end to the framework at E³ and at the opposite ends 20 connected by connecting-rods E⁴ with the cranks E⁵ of the crank-shaft N. Extending in the opposite direction from the upper end of the central connecting-rod E⁴ is a lever E⁶, pivoted at E' of the frame and having a 25 downwardly-extending link E⁸, connected with the reciprocating bed E⁹ of the envelope, business-card, or return-card printing mechanism. The reciprocating beds, it will be understood, are guided, as usual, in right lines, 30 as by guides E¹⁰.

The printing of the body of the letter and emphasized matter takes place through the ink-ribbon, inasmuch as it is desired that this portion of the printed matter shall simulate ordinary type-writing, although as a substitute for the ink-ribbon arrangement type 40 may be employed which give impressions corresponding to the impressions of an ordinary type-writer, as is well understood in this art. The type for printing the letter-head and business or return card on the envelopes, however, are inked directly by an ink mechanism which applies the ink after 45 each impression; the movement of the inking mechanism being controlled by the movements of the beds. In the preferred arrangement an inking-disk D² is arranged at one end of the bed D', but inclined upwardly at an angle thereto, and inking-rollers D³, 50 pivotally mounted on the ends of swinging arms D⁴ are adapted to traverse both the ink plate or disk and face of the type held in the chase. The arms D⁴ are extensible against the tension of springs D⁵ and at their 55 upper ends are pivotally mounted in supports D⁶, rigid with the bed D', so as to rise and fall therewith. Oscillatory motion is imparted to the swinging arms and inking-rollers by the slotted bell-crank extensions 60 D⁷ on the arms D⁴ engaging with a rod D⁸,

held in brackets D⁹, fixed on the frame of the machine. With this arrangement as the bed D' rises the arms D⁴ and inking-rollers will be swung from the position shown in Fig. 11 inwardly across the face of the type held in the 70 chase d, and as the platen then again descends said arms and inking-rollers will be swung out to the position shown in said Fig. 11, as will be readily understood from an inspection of Figs. 12, 13, and 14, where the 75 arms and inking-rollers are shown in several positions occupied by them during their movement, and the reciprocating bed is indicated by full and dotted lines in corresponding positions. The ink-plate or ink- 80 disk may be of the usual rotary type, and rotation may be imparted thereto by gearing D¹⁰, to which intermittent motion is imparted by ratchet-wheel D¹¹ and spring-pressed pawl D¹² on a fixed part of the frame, 85 adapted to engage with the ratchet-wheel D¹¹ as the beds rise, thereby rotating the inking-disk, but permitting the gearing and plate to remain stationary during the descent of the bed. Ink may be supplied to the inking- 90 disk from a feeder D¹³ with a transfer-roller D¹⁴, normally held by a spring D¹⁵ in contact with the ink-supply, but adapted to be moved out of engagement with the ink-supply and into engagement with the inking- 95 disk by the depression of the bed, as will be readily understood from the full and dotted line positions of the transfer-roller in Fig. 11.

By reference to Figs. 2 and 3 it will be seen that the inking mechanism for the printing device K for printing the business or return card on the envelope is in all respects similar to the inking mechanism just described, and hence a specific description of the same is thought to be unnecessary. 100

As before stated, in the particular machine embodied in this application the printing of the body of the letter and the emphasized matter takes place through ink-ribbons, and the mechanism for shifting the ribbons, so as 110 to present new surfaces at the impression-points, is shown in Figs. 15, 16, and 17. By reference to these figures it will be seen that ink-ribbon F' is reversely wound on rollers F², and between the rollers it is guided by 115 rollers f', located above the platen and in such position that the intermediate portion of the ribbon will be depressed by the type in the chase when the bed is brought down for printing. (See Fig. 15.) While separate ribbons are employed for the body of the letter and the emphasized matter, the rollers for said ribbons are simply continuations, as shown clearly in Fig. 16, and consequently a single ribbon-operating mechanism may be utilized for shifting both ribbons simultaneously. 120 This shifting mechanism embodies ratchet-wheels F³ on the ends of the rollers F² and means whereby the ribbon will be fed in either direction, the direction of feed being 125 130

automatically shifted or reversed before the ribbon has reached the limit of its movement in either direction. The feeding mechanism embodies two rock-shafts f^2 , connected by a rod f^3 and adapted to be oscillated through the engagement of an arm f^4 with a vertical pull-rod f^5 , suspended from the lever E^2 of the bed-operating mechanism. The pull-rod f^5 during its upward movement engages the arm f^4 and elevates it until tripped out of engagement with said arm by an adjustable trip projection f^6 engaging an incline f^7 on the side of the rod. It is obvious that by adjusting the trip projection f^6 the extent of ribbon-feed at each movement of the bed may be accurately controlled. Each of the rock-shafts f^2 carries a spring-pressed pawl F^4 , the blocks F^5 in which the pawls are mounted being movable longitudinally of the rock-shafts and adapted to oscillate in unison therewith. One or the other of the pawls is always held in position to engage its appropriate ratchet-wheel by the reverse feed-controlling mechanism. The latter embodies a centrally-pivoted frame F^6 , having arms F^7 embracing the pawl-carrying blocks F^5 and adapted when shifted in one direction to move one of the pawls out of engagement with its ratchet-wheel and the other of the pawls into engagement with its ratchet-wheel, the shifting or pivoted frame F^6 itself being held in one position or the other by a spring F^8 , working across its center of movement, so as to effect the final movement of the pawls with a quick motion, as will be readily understood. A lever F^9 , pivoted on a fixed portion of the frame, is provided with rollers f^8 , adapted to bear against the ribbon being wound on the winding-rollers f^2 , so as to be tilted in one direction or the other in accordance with the variations in the diameters of the rolls of ribbon, and this lever F^9 when tilted in one direction or the other co-operates with one or the other of a pair of bell-crank levers f^9 , having bifurcated ends embracing the shifting-lever F^6 , so as to shift the latter in one direction or the other. For instance, as one roll of ribbon increases in diameter the lever F^9 is depressed at that end and gradually shifts the bell-crank lever f^9 , together with the shifting-lever F^6 , until the spring F^8 moves up to its center and slightly across the center, when the spring asserts itself and shifts one pawl F^4 out of engagement with its ratchet-wheel and the other pawl F^4 into engagement with its ratchet-wheel, thereby reversing the direction of ribbon-feed. To hold the ratchet-wheels during the reverse oscillations of their operating-pawls, holding-pawls f^{10} are mounted on the shifted lever F^6 , said holding-pawls being shifted by the latter in unison with the operating-pawls into and out of engagement with the ratchet-wheels.

65. The mechanism for printing the signatures

(designated generally by the letter G in Fig. 1) is shown in detail in Figs. 20, 21, 22, and 23. By reference to these figures it will be seen that the signature-printing mechanism is adapted to print direct preferably from a facsimile rubber impression-surface, so as to simulate as far as possible a written signature. The mechanism employed embodies to some extent the familiar principle of operation employed in the ordinary hand-stamp with a reversible reciprocating bed, special features of construction being introduced in order to adapt the mechanism for use in the mechanical printing mechanism and in order to permit of the adjustment of the chase or printing-bed, so as to place the signature in any desired position on the letter-sheet.

The rubber type or signature-facsimile-printing surface is indicated at g , mounted in a reciprocating reversible bed G' , the bed being reversed during its reciprocation in the well-understood manner by operating projections g' on the bed and fixed portion of the frame, respectively, so as to receive ink from an ink-pad G^2 , located above the bed. The said ink-pad and frame G^3 , in which the bed is guided, is made adjustable transversely of the line of paper-feed on cross-bars G^4 of the main frame, and the bed-carrying yoke G^5 is guided by the frame G^3 , so as to reciprocate vertically in right lines. In order to reciprocate the yoke G^5 , it is connected with a vertically-reciprocating head G^6 , guided in the main frame at G^7 and connected through the link E' with one of the operating-levers E^2 before described. The connection between the yoke G^5 and the head G^6 is preferably formed by a T-slot in which lateral wings on the head G^6 engage, whereby the said head G^6 while itself reciprocating vertically in right lines and in a definite path will permit of the sliding of the yoke G^5 and bed to any position transversely of the paper-feed. The arrangement is such that the signature-printing mechanism as an entirety may be adjusted with relation to the fixed portion of the frame of the machine and with relation to its operating-head G^6 to any position, and at the same time the operating connections will be properly maintained.

The impressions of the printing mechanism so far described in detail are made simultaneously, but on different letter-sheets or portions of the strip of paper being drawn through the printing mechanism and which portions correspond to the different sheets when severed from the strip. For properly supporting and guiding the strip during its passage through the printing mechanism it is preferably run in guiding-clips A^{10} , secured to the fixed frame of the machine by bolts or screws a^{10} , whereby the clips may be spaced to accommodate wide or narrow paper. The clips a^{10} are preferably so arranged as to support the paper free from the platens, for

which purpose they are extended upwardly and inwardly, as best shown in Figs. 18 and 19, where the paper strip is represented by the letter A¹¹ and the lines on which the strip is to be subsequently severed are indicated by the dotted cross-lines in said Fig. 18.

When the paper passes from the signature-printing mechanism, it is presented to the mechanism for printing the names, addresses, and salutations, the latter mechanism being such as to impress the individual characters or letters at the proper points on the sheet of paper, the type for impressing the names all having a common printing-point. The same is true of the type for printing the different lines of the addresses and salutations. In other words, each line of printing is printed by a different set of type, all of the type of each set having a common printing-point.

Figs. 24, 25, 26, and 27 illustrate the mechanical construction of the individual character-printing mechanism, and by reference to these figures, particularly Fig. 27, it will be seen that the character-printing devices are arranged in four sets, lettered respectively H', H², H³, and H⁴, each being independent of the other set and each adapted to print in its own particular line—that is to say, the set H' prints the addressee's name, the sets H², H³ the address, and the set H⁴ the salutation. Inasmuch as all possible combinations of characters for different salutations may be made up of comparatively few characters, the set H⁴ need only have a comparatively few individual characters, and hence is shown in a single line, the other sets being shown in two lines in order to economize space and to provide for the use of a large number of characters. Each set of character-printing devices is carried by a frame separate from the others and lettered, respectively, h', h², h³, and h⁴. Each set of characters and its frame is independently adjustable on the side frames H⁵ by means of set-screws h⁵, so as to be capable of an adjustment both longitudinally and transversely for properly positioning the sets with relation to each other or so as to vary their relative printing-points, together with the arrangement and location of the printed matter on the letter-sheet. For convenience in adjusting the whole body of characters or all of the sets as a unit the respective frames when properly positioned may be rigidly connected by cross-frames H⁶. The printing characters themselves are mounted on the lower end of sliding bars h⁷, guided in bearings in cross-pieces of the frames h' h² h³ h⁴, said bars having a sufficient range of movement in the bearings to permit the type or printing characters on their ends to be depressed until the type or printing characters come to rest against the platen or the paper and ribbon overlying the platen. It will be understood that a ribbon is preferably employed with operating mechanisms (not

shown) for feeding the same, said ribbon being indicated at h⁸ in Fig. 25.

The mechanism for depressing the type-bars or character-impressing mechanism is preferably electrically operated and controlled from a punched card to be hereinafter described. It suffices to say at this time that in the machine shown each type-bar is connected through a lever h⁹, connecting-rod h¹⁰, and lever h¹¹ with the armature h¹² of a pair of electromagnets h¹³ h¹⁴, one of said magnets being adapted when a circuit is established therethrough to hold the type-bars elevated, and the other of said magnets being adapted when the circuit is established therethrough to depress the type-bars and effect the printing.

In the preferred arrangement the circuit is broken through one of the electromagnets at practically the same instant when it is established through the other. Thus one or the other of the electromagnets is energized at all times, whereby a positive action is secured without the necessity of providing power to overcome spring or gravity pressure, and to this extent the consumption of power is economized.

In Fig. 26 a general arrangement of the circuits is shown in connection with grammatic representations of both a portion of the printing mechanism for printing the names and addresses on the letter-sheet and on the envelope, for it will be understood that the mechanism for printing names and addresses on the envelope is a substantially duplicate of that for printing on the letter-sheet, save that in the envelop-printing mechanism the set of characters for printing the salutation may be entirely omitted. In said Fig. 26 the envelop-printing mechanism L and the letter-sheet-printing mechanism H are shown associated in the same circuit—that is to say, when the circuit for printing a certain character in the letter-sheet set is energized said circuit also energizes the same character-printing mechanism in the envelop-printer. The source of electrical energy may be a battery L', and from this battery the circuit passes to a switch or movable contact-piece L², working between fixed contacts L³ L⁴. From the contact L³ the circuit passes to similar magnets h¹³ of both the letter-sheet and envelope printing devices and thence back to battery, while from the contact L⁴ the circuit passes to similar magnets h¹⁴ of both the envelope and letter-sheet printing devices, and thence back to battery. Obviously with this arrangement if the switch or movable contact-piece be moved out of engagement with the contact L⁴ and into engagement with the contact L³ the printing devices controlled by that circuit will be operated to print corresponding characters, and upon the reestablishment of the circuit through a contact L⁴ the printing devices

will be withdrawn by the magnets h^{14} . Each character-printing mechanism has its own operating electromagnets, circuit, and contacts, and the several movable contact-pieces 5 L^2 are adapted to be controlled by perforated cards or controllers automatically handled and fed through the machine by mechanism to be now described, the feed of the cards and paper being coördinated.

10 *Controller-handling mechanism.*—This controller-handling mechanism is shown in detail in Figs. 28 to 36, inclusive, and one of the controllers is shown in Fig. 37.

The mechanism whereby the feed movements are imparted to the shaft P^{13} have heretofore been described, and it is only necessary at this time to recall that said shaft is given a long feed movement followed by a pause, and the pause followed by a succession of short feed movements corresponding in number to the number of characters within the extremes of the name, address, and salutation. The upper end of the shaft P^{13} carries a sprocket-wheel R , round which a 25 card-feeding chain R' passes to a second sprocket-wheel R^2 ; the latter being simply an idler. The cards J , previously prepared with proper punched apertures therein, are held in a hopper or stack R^5 in position to be 30 drawn therefrom one at a time and presented to spring-pressed clips or jaws r' on the chain, and in order to feed the cards in parallelism chains are arranged at opposite ends of the cards—that is to say, a second feed-chain R^3 35 is provided opposite the chain R' and passing round similar sprocket-wheels, one of which R^4 is connected through a train of gearing embodying miter-gears R^6 with the shaft P^{13} , whereby the said feed-chains will be given 40 uniform movements for feeding the cards forwardly.

For drawing the cards from the bottom of the stack or hopper individually and presenting the same to the spring-clips of the feed-chains a reciprocatory feeding device is provided, embodying a cross-bar S , Fig. 33, having a large number of pointed pins on its upper surface adapted when pressed upwardly to engage the under surface of the lowermost 45 cards, and when drawn forwardly to draw said card from the bottom of the pile or stack, as shown clearly in Fig. 30. This cross-bar S constitutes one side of a frame S' , pivoted in a slide S^2 , guided in ways on the main 50 frame and adapted to be reciprocated by oppositely-rotating arms S^3 , mounted on intermeshing gear-wheels S^4 , carried by shafts S^5 ; one of which receives its motion through bevel-gear S^6 from the shaft P^{13} . The arms 55 engage shoulders S^{21} on the slide, and their position is such that the reciprocatory feeder is advanced in proper time for presenting each succeeding card to the feed-chain, so that its forward edge will be in proximity to the rear 60 edge of the preceding card—for instance, as

shown in said Fig. 30. The reciprocatory feeder-frame, including the cross-bar having the pins thereon, is guided in its reciprocations by ways in the main frame at each end and lettered in Figs. 33, 35, and 36 with the 7c letter S^7 , and in which ways pins S^8 on the said feeder-frame work. The ways S^7 , it will be noted, constitute loops having upper and lower reaches, in the upper one of which the pins S^8 travel forwardly and in the other 75 of which they travel rearwardly, and in order to transfer the feeder-frame from the lower to the upper reach the said frame is preferably normally under the influence of a spring S^9 , tending to hold it up, so as to engage the 80 cards and enter the upper reach, and when the frame has been moved forwardly to feed a card out of the stack the said feeder-frame is depressed by the pins S^8 passing into pockets s in the forwardly-extending arms s' 85 of a rocker, pivoted to the main frame at s^2 and by the latter transferred to the lower reach. The said rocker embodies a cross-bar s^3 , located below the pivots s^2 and in position to be engaged by pins s^4 on the reciprocatory 90 slide S^2 . Said pins s^4 are adjustable in the slide S^2 and so located that when the slide S^2 advances the pins will by engaging the cross-bar s^3 depress the rocker-frame, thereby 95 transferring the feeder-frame from the upper to the lower reach of the guideway. When the slide S^2 returns to its rear position, the other pins s^4 striking the cross-bar s^3 will 100 elevate the rocker-frame into position to again receive the guiding-pins on the feeder-frame. In order to hold the rocker-frame in position, either elevated or depressed, until positively moved in the opposite direction, springs s^5 are provided on the main frame, and coöperating projections and recesses in 105 the springs and on the rocker-frame, respectively, will serve to maintain the rocker-frame in either position, as will be readily understood by those skilled in the art. The 110 spring-clips or grippers R' on the feed-chains are opened automatically as the said grippers approach the position for receiving a card, the opening means preferably consisting of a pair of inclines T , between which the rear ends of the grippers pass and out of engagement with which they pass at the instant 115 when the card is to be gripped. For discharging the cards from the grippers similar inclines T' are provided at the rear end of the card-feeding mechanism.

Between the feed-chains is arranged a channel-way for the passage of the cards, said channel-way preferably consisting of top and bottom plates T^2 , which make fairly close contact with the two surfaces of the cards. 120 In their transit through the channel the said cards are adapted to pass apertures t , extending transversely and terminating in proximity to the movable contacts L^2 , before described. Thus the cards themselves form 125

valves controlling the ducts t . To effect the operation of the movable contacts L^2 , the said ducts t are supplied with air-pressure, as from a reservoir or tank t' , and when air-pressure is admitted through any particular duct t its corresponding contact L^2 will be depressed to effect the operation of the character-printing devices controlled thereby. In order to simplify the construction as far as possible, the movable contacts are adapted to fit into slots or recesses in the under side of the block having the ducts therein, and thus, in effect, each of said contacts forms a piston, against which the air-pressure will act and whereby the contact will be moved to break one branch of the circuit and establish the other, as heretofore described.

One of the cards J is shown in detail in Fig. 37, and in the preferred arrangement it is divided into sections, the perforations in the section j being properly positioned to actuate the name-printing mechanism, the perforations in the section j' to actuate the local-address-printing mechanism, the perforations in the section j^2 to actuate the city and State printing mechanism, and the perforations in the section j^3 to actuate the salutation-printing mechanism. It is obvious that by properly positioning the perforations any desired combination of letters and marks may be designated in the card in any of the sections, and in this preferred construction the width of the card is made great enough to embrace a number of feed movements corresponding to the number of feed movements of the paper-feed within the limits of the name, address, and salutation, although the range of such movements may be less than that of the paper-feed. The long feed of the paper for bringing a new sheet into position for receiving the individual character impressions corresponds to the long feed of the cards for shifting one card out of position in the channel-way to register with the air-ducts and a new card into position for registration therewith, and the short or step-by-step feeds in both the paper and card feeding mechanism are synchronized, whereby when a card has been fed to present a new line of perforations the paper will have been correspondingly fed to present a new area at the printing-points of the individual character-impressing mechanisms.

Envelop-feeding devices.—In order that the names and addresses may be printed on the envelops simultaneously with the printing of the names and addresses on the letter-sheets and by mechanism controlled by the same means, the envelop-feed, paper-feed, and controller or card feed are all coöordinated through the mechanism heretofore described. Thus it will be understood that the envelops are given a long rapid feed in order to position succeeding envelops for receiving the individual character impressions and are

then given a succession of short feeds as the individual characters are impressed thereon, the succession of short feeds being again followed by a long and rapid feed to position the next envelop.

The envelop-feeding mechanism is best shown in Figs. 38 to 47, and the entire mechanism receives its feed movements from the shaft Q^{13} , driven as heretofore described in connection with Figs. 40, 41, 42, and 43. Extending parallel with the path through which the envelops are fed are two feed-chains U , running around sprocket-wheels $U' U^2 U^3 U^4$, the sprocket-wheel U' being on the upper end of the shaft Q^{13} , and the sprocket-wheel U^2 is rotated in unison with the sprocket-wheel U' through gearing embodying the shafts u and gears u' and u^2 . On each of the feed-chains are a series of spring-clips U^5 , adapted to automatically close on opposite edges of the envelop and draw the same along in accordance with the feed movements of the chains. Such spring-clips U^5 are opened for the reception of the envelops by inclines U^6 , carried by the frame immediately over the sprocket-wheels U' and U^2 , and automatically close on the envelop when they move out of engagement with the inclines. They are again opened to discharge the envelops by inclines U^7 , located at the opposite ends of the chains or in proximity to the sprocket-wheels U^3 and U^4 .

The envelops are stacked in a hopper V and are adapted to be drawn therefrom singly and in succession by a reciprocatory feeding device which engages the lowermost envelop of the stack and advances the same into position for being grasped by the spring-clips on the feeding-chains. The reciprocatory envelop-feeding devices embody a reciprocating slide V' , mounted in ways in a laterally-adjustable frame, to be presently described, and has reciprocatory movement imparted thereto by a pair of arms or projections V^2 , mounted on oppositely-rotating shafts V^3 . Said shafts V^3 are geared together, and one of them receives its motion from the shaft Q^{13} through bevel-gears V^4 , as best shown in Figs. 39, 40, and 41. The arms or projections V^2 engage oppositely-located shoulders V^5 in the under side of the slide V' , and said arms and shoulders are so positioned that the slide will be reciprocated in proper time to advance the envelop so as to be grasped by the feed-chain in close sequence. Pivoted to the forward end of the slide V' is a feeder-frame W , Fig. 46, the rear end of said frame carrying a laterally-adjustable cross-piece w , having upwardly-projecting pointed teeth or pins thereon adapted to engage the under surface of the lowermost envelop in the stack. The frame W is pressed upwardly into engagement with the envelops, preferably by a spring w' , and it is guided in its reciprocatory movements by

pins w^2 , working in guideways W^2 in the machine-frame. The guideways W^2 are made in the form of a loop or with top and bottom reaches, whereby the feeder-frame W is advanced to feed an envelop while being guided by the upper reach of the guideway, but will be returned to its initial position through the lower reach of the guideway and with the teeth or pins out of contact with the envelop. 5 To make the movement more positive and to insure the proper freeing of the envelop from the teeth or pins, the feeder-frame W is moved downwardly at the forward end of its stroke by a rocker-frame W^3 , pivoted at w^3 in the frame of the machine and adapted to be elevated and depressed by the engagement of pins w^4 on the slide with the bell-crank arms W^4 of the rocker-frame. The forward ends or arms of the rocker-frame W^3 10 are provided with recesses W^5 , into which the pins w^2 pass and in which said pins are held until the pins W^4 operate to depress the rocker-frame and bring the guide-pins w^2 into alignment with the lower reach of the 15 guideway W^2 . The rocker-frame may be held in elevated or depressed position by friction or spring-pressed holding means, such as are well understood in the arts or, for 20 instance, as described in connection with the card-feeding mechanism. 25

Inasmuch as it is desirable that the machine should have the capacity for handling different size envelops, provision is made for adjusting the distance between the envelop- 30 feeding chains as well as the width of the stack and guiding mechanism for the envelops. With this end in view the slide V' , together with the shafts for the sprocket-wheels U^2 and U^4 , are mounted in a laterally-adjustable section X of the frame. The adjustable frame X is mounted on transversely-extending screws X' , journaled in the main frame and adapted to be rotated in unison in one direction or the other by worm-gears X^2 , with 35 which worms X^3 on a hand-operated shaft X^4 are adapted to mesh. It is obvious that by rotating the screws X' the whole adjustable section X of the frame, together with the reciprocating feeding mechanism and one of 40 the feed-chains, will be adjusted. 45

The engagement of the gearing u^2 for driving the adjustable feed-chain is maintained by making the gear-wheel u^2 adjustable on its shaft u . This adjustment may be effected, 50 as shown, by loosening the gear-wheel on its shaft and after the parts have been adjusted moving the same into gear and again tightening it on its shaft by the means of the usual set-screw. The shoulders V^5 on the under 55 side of the slide V' are made of such width as to coöperate with the arms V^2 in any position of adjustment, and in order that the cross-piece w may always coöperate centrally with the envelop it is made adjustable laterally 60 on the end of the frame W by means of set-

screws working in slots in the cross-piece, as shown clearly in Fig. 46. The sides of the stack and adjustable section of the frame may be locked in adjusted position by toggle-links X^{15} , adapted to be clamped together at the 70 joint by a jam-nut X^{16} , Figs. 44 and 45. Longitudinal slack may be taken out of the feed-chains by adjusting the sprocket-wheels U^3 U^4 , for which purpose the shafts carrying said sprocket-wheels are shown as mounted 75 in bearings Y , adapted to be adjusted by screws Y' , although it is obvious that any other and well-known equivalent means may be employed for this purpose.

In operation the paper strip, envelops, 80 and controllers or cards are all fed simultaneously, the envelop - feed and paper - feed throughout the period when the individual printing characters are impressed thereon preferably being uniform in extent; but it is 85 obvious that while all of the feeds mentioned must be synchronized they may vary in extent, inasmuch as the cards may be comparatively narrow and their feed comparatively short, while the envelops may be long 90 envelops and their feed correspondingly long as compared with the paper-feed.

The cards and envelops may be discharged into any suitable receivers or deposited in stacks; but the paper strip as it passes away 95 from the individual character - impressing mechanism and feeding mechanism is pushed through the cutting devices for severing it into sheets. This cutting mechanism is shown in detail in Figs. 7, 9, and 10 and will 100 be seen to consist of an oscillatory cutter-blade C' , pivoted at one end to the frame and at the opposite end pivotally connected with a vertically-extending operating arm or lever C^2 , said arm or lever extending down into 105 proximity to the main shaft N . On the shaft N is located a collar C^3 , carrying a tooth or projection C^4 , adapted to engage a shoulder C^5 on the arm or rod C^2 . The lower end of the rod or arm C^2 is guided by a fixed pin or 110 projection C^6 , and consequently as the shaft N rotates the projection C^4 will engage the shoulder C^5 , depress the cutter-blade against the tension of its spring C^7 , severing the strip of paper, and finally the said projection C^4 115 will ride out of engagement with the shoulder C^5 , releasing the cutter and permitting it to return to its normal position.

From the foregoing it will be seen that each revolution of the shaft N takes place in the 120 time required for printing complete one letter-sheet and one envelop and in the time required for feeding one card, this including the long rapid feed and the succession of short step-by-step feeds. It is obvious that with 125 the arrangement of mechanism described the capacity of the machine in a given time is very large. The letter-sheet and envelops will be discharged from the machine in correct order for being brought together without 130

sorting, and both are in such order as to permit of ready verification with the cards which control the printing thereon.

The cards, in effect, constitute a mailing list, and in the present machine such list may be added to, changed, or rearranged, as described, without in any wise affecting the operation of the machine.

Having thus described my invention, what I claim as new, and desire to secure by Letters Patent, is—

1. In a circular-letter-printing machine, the combination with mechanism for simultaneously impressing the characters composing the body of a letter and mechanism for successively impressing characters composing the name and address, of paper-feeding mechanism having a long and a succession of short-feed movements; substantially as described.

2. In a circular-letter-printing machine, the combination with mechanism embodying an impression-surface for printing the body of a letter and mechanism for successively impressing characters composing the name and address, of a paper-feeding mechanism having a long and a succession of short feed movements; substantially as described.

3. In a circular-letter-printing machine, the combination with a paper-strip-feeding mechanism having differential intermittent feed movements, of printing mechanism embodying an impression-surface for printing the body of the letter and mechanism for impressing a succession of names and addresses upon the paper at a point remote from the impression-surface for the body of the letter; substantially as described.

4. In a circular-letter-printing machine, the combination with a paper-strip feed having differential intermittent feed movements, of correlated printing mechanism for making separate impressions corresponding to the feed movements, whereby the body of the letter and names and addresses may be printed separately but in proper relation to each other on the strip; substantially as described.

5. In a circular-letter-printing machine, the combination with a paper-strip feed having alternating long and a succession of short feed movements, a single long and a succession of short feed movements corresponding to the feed of a single letter-sheet, of printing mechanism embodying an impression-surface composed of characters connected for simultaneous movement, and a series of impression-surfaces operating in succession and in coördination with the short feed movements of the paper; substantially as described.

6. In a circular-letter-printing machine, the combination with printing mechanism embodying an impression-surface comprising a number of characters connected for simultaneous impression, and a series of individual

printing characters adapted to be impressed in succession, of a paper-strip feed having a succession of intermittent short feed movements coöordinated with the impression of individual characters and alternating with long feed movements coöordinated with the simultaneous impression of a number of characters; substantially as described.

7. In a circular-letter-printing machine, the combination with a paper-strip feed having intermittent feed movements, of name and address printing mechanism embodying successively operating individual character-impressing mechanism coöordinated with the feed movements, a printing mechanism having an impression-surface comprising a group of characters assembled for simultaneous operation and an operating mechanism coöordinated with the individual character-impressing mechanism to give a single impression of the assembled characters for each name and address printed by a succession of individual characters; substantially as described.

8. In a circular-letter-printing machine, the combination with printing mechanism embodying, first intermittently-operated printing characters assembled for simultaneous operation to print matter common to all of the letters, and, secondly, individual separately-operating printing characters for printing matter appropriate to each letter, of means for operating a succession of the individual printing characters between succeeding operations of the assembled printing characters.

9. In a circular-letter-printing machine, the combination with printing mechanism embodying intermittently-operated printing characters assembled for simultaneous operation to print matter common to all of the letters, and separately-operating printing characters for printing matter appropriate to each individual letter, of controlling means for the separately-operated printing characters embodying designations corresponding to matter appropriate to each letter and different from matter printed on other letters.

10. In a circular-letter-printing machine, the combination with printing mechanism embodying intermittently-operated printing characters assembled for simultaneous operation to print matter common to all of the letters, and separately-operating printing characters for printing matter appropriate to each individual letter, of a succession of controllers, for the separately-operated printing characters, one for each letter and feeding mechanism for feeding said controllers in succession, in accordance with the number of impressions of the assembled printing characters.

11. In a circular-letter-printing machine, the combination with printing mechanism, embodying printing characters assembled for simultaneous operation to print matter

- common to all of the letters, separately-operated printing characters for printing matter appropriate to each individual letter and controllers for the latter, corresponding to 5 the number of letters to be printed, of an operating mechanism for the assembled printing characters and a feeding mechanism for the controllers timed to feed in succession a number of controllers corresponding to the 10 number of operations of the assembled printing characters; substantially as described.
12. In a circular-letter-printing machine, the combination with printing mechanism embodying printing characters assembled 15 for simultaneous operation to print matter common to all the letters and individually-operated printing characters for printing matter appropriate for each letter, of an operating mechanism for the assembled printing 20 characters and an intermittent paper-feed driven by the operating mechanism and having movements corresponding to the feed in printing individual characters.
13. In a circular-letter-printing machine, 25 the combination with printing mechanism embodying printing characters assembled for simultaneous operation to print matter common to all the letters and individually-operated printing characters for printing 30 matter appropriate for each letter, of operating mechanism, and an intermittent differential paper-feed driven by the operating mechanism; substantially as described.
14. In a circular-letter-printing machine, 35 the combination with printing mechanism embodying printing characters assembled for simultaneous operation to print matter common to all the letters and individually-operated printing characters for printing 40 matter appropriate for each letter, of operating mechanism and an intermittent paper-feed having a succession of short feed movements corresponding to the individual character impressions, alternating with relatively long 45 feed movements; substantially as described.
15. In a circular-letter-printing machine, the combination with a printing mechanism embodying printing characters assembled 50 for simultaneous operation to print matter common to all the letters and individually-operated printing characters for printing 55 matter appropriate for each letter and controllers for the last-mentioned printing characters having appropriate matter designated thereon, of feeding mechanism for the paper and feeding mechanism for the controllers, said feeding mechanisms having synchronous intermittent feed movements; substantially as described.
16. In a circular-letter-printing machine, 60 the combination with a printing mechanism embodying printing characters assembled for simultaneous operation to print matter common to all the letters and individually-operated printing characters for printing 65

matter appropriate for each letter and controllers for the last-mentioned printing characters having appropriate matter designated thereon, of feeding mechanism for the paper and feeding mechanism for the controllers, 70 said feeding mechanisms having synchronous differential intermittent feed movements; substantially as described.

17. In a circular-letter and envelop printing machine, the combination with printing 75 mechanism embodying separate sets of printing characters each assembled for simultaneous operation, one for printing matter common to all the letters and the other for printing matter common to all the envelopes and 80 individual separately-operated character-impressing mechanism for printing matter appropriate for each letter and its envelop, of controllers for the individual character-impressing mechanism and paper, envelop and controller feeding mechanisms having intermittent synchronous feed movements whereby duplicate matter may be printed on an envelop and its corresponding letter-sheet; substantially as described.

18. In a circular-letter and envelop printing machine, the combination with duplicate individual separately-operating character-impressing mechanism, for impressing similar matter on letter-sheets and envelopes and controllers each controlling both said printing mechanisms, of paper, envelop and controller feeding mechanisms having intermittent synchronous feed movements, whereby the same matter designated in a controller 95 will be simultaneously impressed on a letter-sheet and its corresponding envelop; substantially as described.

19. In a circular-letter and envelop printing machine, the combination with duplicate 105 individual separately-operating character-impressing mechanism, for impressing similar matter on letter-sheets and envelopes and controllers each controlling both said printing mechanisms, of paper, envelop and controller feeding mechanisms having differential intermittent synchronous feed movements, whereby the same matter designated in a controller will be simultaneously impressed on a letter-sheet and its corresponding 110 envelop; substantially as described.

20. In a circular-letter-printing machine, the combination with printing mechanism embodying printing characters assembled for simultaneous operation and individual separately-operated printing characters, of a feeding mechanism embodying driving and driven shafts and two trains of gearing between said shafts each train embodying a mutilated gear, whereby the trains of gearing 120 are alternately effective in transmitting power to the driven shaft.

21. In a circular-letter-printing machine, the combination with printing mechanism embodying printing characters assembled for 125

- simultaneous operation and individual separately-operated printing characters, of a feeding mechanism embodying driving and driven shafts and two trains of gearing between said shafts, each train embodying a mutilated gear and set for alternate action and one of said trains embodying step-by-step feed mechanism; substantially as described.
22. In a circular-letter-printing machine, the combination with printing mechanism embodying printing characters assembled for simultaneous operation and individual separately-operated printing characters, of a feeding mechanism embodying driving and driven shafts, two trains of gearing between said shafts, each train including a mutilated gear and set for alternate action and one of said trains embodying a step-by-step feed mechanism including a mutilated gear; substantially as described.
23. In a circular-letter-printing machine, the combination with printing mechanism embodying printing characters assembled for simultaneous operation and individual separately-operated printing characters, of a feeding mechanism embodying driving and driven shafts, two trains of gearing between said shafts, each train including a mutilated gear and set for alternate action, and one of said trains including a worm-segment and worm-gear with which it meshes intermittently; substantially as described.
24. In a circular-letter-printing machine, the combination with printing mechanism embodying printing characters assembled for simultaneous operation and individual separately-operated printing characters, of a feeding mechanism embodying driving and driven shafts, two trains of gearing between said shafts, each train including a mutilated gear and set for alternate action, and one of said trains including a worm-segment and mutilated worm-gear with which it meshes intermittently; substantially as described.
25. In a circular-letter-printing machine, the combination with letter-sheet and envelop printing mechanism and controlling means for determining the characters to be printed, of feed mechanisms for the paper, envelops and controlling means connected by gearing and each embodying driving and driven shafts with two trains of gearing between said shafts, each train including a mutilated gear, similar mutilated gears in all the mechanisms being set to act simultaneously; substantially as described.
26. In a circular-letter-printing machine, the combination with letter-sheet and envelop printing mechanism and controlling means for determining the characters to be printed, of intermittently-operating feed mechanism for the paper, envelops and controlling means embodying driving and driven shafts and two trains of gearing between said

shafts, each including a mutilated gear and acting in alternation, whereby the feed movements may be differential; substantially as described.

27. In a circular-letter-printing machine, the combination with letter-sheet and envelop printing mechanism and controlling means for determining the characters to be printed, of feed mechanism for the paper, envelops and controlling means embodying driving and driven shafts, two trains of gearing between said shafts each including a mutilated gear and acting in alternation and one of said trains including a step-by-step feed mechanism whereby alternating long and a succession of short feed movements may be effected; substantially as described.

28. In a circular-letter-printing machine, the combination with individual character-impressing mechanism having a common printing-point, of a paper-feeding mechanism embodying a driving-shaft and a driven shaft, two trains of gearing between said shafts each including a mutilated gear and adapted to act in alternation and one of said trains including a step-by-step feed mechanism coöordinated with the operation of the character-impressing mechanism, whereby a succession of characters may be impressed when one train is in action and a long feed be effected when the other train is in action and between groups of impressions; substantially as described.

29. In a circular-letter-printing machine, the combination with the printing mechanism, of a paper-feeding mechanism embodying feeding-rolls geared together, a mutilated worm-gear and a mutilated spur-gear carried by one of the rolls, a segmental worm adapted to mesh with the worm-gear, a gear-wheel for rotating the worm, a drive-shaft, a mutilated gear moved by the shaft adapted to mesh with the gear-wheel for rotating the worm and a gear moved by the shaft adapted to mesh with the mutilated gear on the feed-roll; substantially as described.

30. In a circular-letter-printing machine, the combination with the paper-strip-feeding mechanism and means for printing the body of the letter and name address and salutation, of a signature-printing mechanism embodying a vertically-reciprocal bed adjustable transversely of the line of paper-feed to position the signature on the letter-sheet; substantially as described.

31. In a circular-letter-printing machine, the combination with the paper-strip-feeding mechanism and means for printing the body of the letter and names, address and salutation, of a signature-printing mechanism embodying a reciprocating reversible bed and an inking-pad therefor both adjustable transversely of the line of paper-feed to position the signature on the sheet; substantially as described.

32. In a circular-letter-printing machine, the combination with printing mechanisms arranged in succession, inking means for one mechanism and an ink-ribbon interposed in the other mechanism, of paper-strip-feeding mechanism having intermittent feed movements for presenting portions of the strip corresponding to letter-sheets to the printing mechanisms in succession and means for severing the strip into sheets; substantially as described.

33. In a circular-letter-printing machine, the combination with a letter-head-printing mechanism having an impression-surface acting directly on the paper and a letter-printing mechanism having an impression-surface and an ink-ribbon through which the impression-surface acts on the paper, of a paper-strip-feeding mechanism having intermittent feed movements for presenting sections of the paper to the printing mechanisms in succession and cutting mechanism for severing the strip into sheets; substantially as described.

34. In a circular-letter-printing machine, the combination with a reciprocatory bed adapted to carry a plurality of forms for simultaneous impression and a paper-strip feed having intermittent feed movements for presenting sections of the paper strip successively to the forms carried by the bed, of an inking mechanism having inking devices movable across a portion of the face of said bed corresponding to the location of one of the forms and an inking-ribbon extending across the face of said bed in position to receive the impression from the other of said forms; substantially as described.

35. In a circular-letter-printing machine, the combination with a reciprocatory bed, an inking-ribbon bridging a portion only of the face of said bed and an inking device embodying inking-rollers movable across another portion of the face of said bed whereby impressions may be made partly by direct action of the impression-surface and partly through an interposed ink-ribbon.

36. In a circular-letter-printing machine, the combination with a reciprocatory bed, an ink-ribbon bridging a portion only of the face of said bed, an inking mechanism embodying inking-rollers movable only across another portion of the face of said bed and means for reciprocating the bed, of a paper-strip-feeding mechanism having intermittent feed movement for transferring portions of the paper strip into position to be successively acted on by the impression-surfaces carried by the bed.

37. In a circular-letter-printing machine, the combination with mechanism embodying collective printing characters with means whereby they are simultaneously impressed to print matter common to all of the letters, of a series of individual character-impressing

mechanisms arranged in different lines for printing the name and address respectively and a paper-strip-feeding mechanism having intermittent feed movements for feeding the paper in direction parallel with the lines of the name and address; substantially as described.

38. In a circular-letter-printing machine, the combination with printing mechanism embodying characters associated for simultaneous operation to print matter common to all of the letters, of a series of individual character-impressing mechanisms, each having a common impression-point and a paper-feed mechanism having differential feed movements; substantially as described.

39. In a circular-letter-printing machine, the combination with printing mechanism embodying printing characters associated for simultaneous operation to print matter common to all of the letters and a paper-strip-feed mechanism having intermittent feed movements, of name and address printing mechanism adjustably mounted with relation to the line of paper-feed, whereby the position of the name and address may be changed; substantially as described.

40. In a circular-letter-printing machine, the combination with a paper-strip-feeding mechanism having intermittent feed movements, of printing mechanism embodying printing characters associated for simultaneous operation to print matter common to all of the letters, an individual character-impressing mechanism mounted in a frame adjustable both longitudinally and laterally of the line of paper-feed for printing matter appropriate for each individual letter; substantially as described.

41. In a circular-letter-printing machine, the combination with a paper-strip-feeding mechanism, having differential intermittent feed movements, of a printing mechanism embodying printing characters associated for simultaneous operation to print matter common to all of the letters and individual separately-operated, printing characters arranged in separate groups each adjustable with relation to the line of paper-feed for printing matter appropriate to each letter; substantially as described.

42. In a circular-letter-printing machine, the combination with a paper-strip-feeding mechanism having intermittent feed movements, of a series of groups of printing devices arranged in parallel planes parallel with the line of paper-feed, for printing different lines of matter appropriate to each letter and separately-adjustable frames in which said printing devices are supported; substantially as described.

43. In a circular-letter-printing machine, the combination with a paper-feed mechanism having intermittent feed movements, of electrically-operated individual character-

impressing mechanism, perforated cards controlling the operation of said mechanism and card-feeding devices having feed movements synchronous with the feed movements of the 5 paper-feed mechanism; substantially as described.

44. In a circular-letter-printing machine, the combination with a paper-strip-feeding mechanism having intermittent feed movements and electrically-operated individual character-impressing devices, of contacts adapted to be operated by pneumatic pressure and controlling the circuits for operating said printing devices, perforated cards controlling the pneumatic pressure for operating the contacts and card-feeding mechanism connected by gearing with the paper-feeding mechanism whereby the paper and cards are fed simultaneously.
45. In a circular-letter-printing machine, the combination with printing mechanism for printing matter common to all of the letters and a printing mechanism for printing matter appropriate to each letter, a perforated-card-handling mechanism for controlling the last-mentioned printing mechanism and embodying feed-chains provided with gripping devices for the cards and having intermittent feed movement and a reciprocatory feeder for advancing the cards to the gripping devices on the feed-chains; substantially as described.

46. In a circular-letter-printing machine, the combination with printing mechanism for printing matter common to all of the letters and printing mechanism controlled by perforated cards for printing matter appropriate to each letter, of paper-feed mechanism having intermittent feed movements and card-feed mechanism having intermittent feed move-

ments, chains provided with gripping devices for the cards and a reciprocatory feeder for advancing the cards to said gripping devices, the said card and paper feeding mechanisms being geared together for synchronous move- 45

47. In a circular-letter-printing machine the combination with printing mechanism for printing matter common to all of the letters and printing mechanism for printing matter 50 appropriate to each letter, of means for controlling the mechanism for printing matter appropriate to each letter, embodying perforated cards, feed-chains for advancing said cards and having intermittent feed movements and a reciprocatory feeder for advancing the cards to the feed-chains with means for positively withdrawing the reciprocatory feeder from engagement with the cards; substantially as described. 55

48. In a printing-machine such as described, the combination with printing mechanism embodying characters assembled for simultaneous operation to make successive duplicate impressions and printing mechanism for making successive different impressions, of a feeding mechanism embodying feed-chains having intermittent feed movements, gripping devices mounted on said chains and a reciprocatory feeder embodying 65 a cross-bar having pointed pins thereon, means for elevating and depressing said cross-bar, means for reciprocating said cross-bar and gearing between said reciprocating means and feed-chains; substantially as de- 70

scribed. 75
